UNITED STATES PATENT OFFICE.

DAVID SHERWOOD KENNEDY, OF BROOKLYN, NEW YORK, ASSIGNOR TO MERGEN-THALER LINOTYPE COMPANY, OF NEW YORK, N. Y., A CORPORATION OF NEW YORK.

TYPOGRAPHICAL MACHINE.

1,115,682.

Specification of Letters Patent.

Patented Nov. 3, 1914.

Application filed August 10, 1914. Serial No. 855,956.

To all whom it may concern:

Be it known that I, DAVID SHERWOOD KENNEDY, a citizen of the United States, residing at Brooklyn, in the county of Kings and State of New York, have invented certain new and useful Improvements in Typographical Machines, of which the following is a specification, reference being had therein to the accompanying drawing.

10 My invention relates to typographical composing machines, such as linotype machines of the general organization represented in Letters Patent of the United States, No. 436532, to O. Mergenthaler, wherein circulating matrices are released by suitable escapement devices from a magazine in the order in which their characters are to appear in print and then assembled in line, the composed line transferred to the face of a mold, the mold filled with molten metal to form a slug or linotype against the matrices which produce the type characters thereon, and the matrices thereafter returned through distributing mechanism to the magazine from which they started.

15 More particularly, it relates to the escapement devices, etc., and comprises means to start or accelerate the matrices when released thereby.

20 In the accompanying drawing, I have shown my invention only in preferred form and by way of example, and as applied to the standard style of mechanism, but obviously many changes and variations may be made therein, and in its mode of application, which will still be comprised within its spirit. Similarly, it may be adapted to other forms of typographical machines, such as typesetters, typecasters and the like,

25 which handle type or dies, instead of matrices. Generally speaking, I desire it to be understood that I do not limit myself to any specific form or embodiment, except in so far as such limitations are specified in the

30 claims.

In the drawing: Figure 1 is a section through the lower end of the magazine, etc., with my improvements embodied therein; and Fig. 2 is a similar view showing the

The matrices X are stored as usual in the magazine A, from which they are released in the desired order and delivered to the assembling mechanism through the channel or raceway B. The releasing means comprise the usual escapement devices, consisting of the pivoted lever C, and the connected pawls D and E, which are alternately projected into the magazine channel to cooperate with the matrices therein, the spring C¹ and reed C² acting to move the escapement lever in opposite directions, all in the manner well understood in the art. The parts so far described, and their mode of operation, are or may be of any suitable description, and in themselves constitute no part of my invention.

My improved accelerating or starting means are in the present instance connected to the lever C, and comprise a short arm F pivotally mounted on the lever, and further means to move it in the direction of the advance of the matrices when the escapement is actuated. In the illustrated form, the arm F is located above the pivotal point of the lever and below the upper pawl E and is projected into the magazine through the opening A¹ by the operation of the escapement. A spring F² connected to the arm gives it its downward or accelerating movement after it enters the magazine. The arm is formed at its end with a beveled nose F³ to engage the side of the opening A¹ and return the arm to its normal position when withdrawn from the channel. The arm is also formed in its edge with a notch F⁴ which is designed to engage at times a fixed pin G, the pin and notch cooperating to allow the arm to be moved by its spring when it is projected into the magazine, and to return the arm to its original position after it is withdrawn, and the pin also serving to hold the arm in proper relation to the escapement when the latter is disconnected from the magazine.

In Fig. 1, the parts are shown in their normal position, with the lower pawl D projected and engaging the lowermost matrix, and with the upper pawl E and the arm F retracted. At this time, the arm F is held

in its uppermost position against the tension of the spring F^2 by the engagement of its nose F^3 in the opening A^1 and of the pin G with the edge of the arm. In Fig. 2, the 5 parts are shown in the reversed position occasioned by the reciprocation of the lever C , namely, with the pawl D retracted and the lowermost matrix X consequently freed, and with the pawl E projected into the path 10 of the second matrix. At this time, the arm F is also projected into the channel above and in proximity to the lower ear of the second proximity to the lower ear of the second matrix and has been moved relatively to the 15 pin G so as to bring the notch F^1 into relation thereto. The spring F^2 is now permitted to act and moves the arm in the direction of the advance of the matrices, and due to its engagement with the second matrix, 20 the latter as well as the matrix below it are started or accelerated downward in the channel. It will be understood that the parts are so disposed and timed that the projection of the arm F and its accelerating 25 action occur when the lower pawl D has released the lowermost matrix.

The improvement is of great advantage not only in overcoming the inertia and quickening the delivery of the matrices, but 30 also in avoiding their occasional liability to stick due to friction or the presence of foreign matter. As already stated, I have shown my invention only in preferred form and by way of example, and as adapted to a 35 particular style of mechanism, but obviously many modifications and alterations therein, and in its mode of application, will suggest themselves to those skilled in the art, without departure from its scope.

40 Having thus described my invention, what I claim and desire to secure by Letters Patent of the United States is as follows:

1. In a typographical machine, the combination of a channeled magazine, an escapement comprising a pair of pawls acting to control the release of type or matrices individually therefrom, and means controlled by the escapement to overcome the 45 inertia of a released type or matrix and accelerate it in its passage from the magazine.

2. In a typographical machine, the combination of a channeled magazine, and an escapement to control the release of type or matrices therefrom, the said escapement 55 carrying means to overcome the inertia of a released type or matrix and accelerate it in its passage from the magazine.

3. In a typographical machine, the combination of a channeled magazine, and an 60 escapement to control the release of type or matrices therefrom, said escapement carrying a spring-actuated arm to overcome the inertia of a released type or matrix and accelerate it in its passage from the magazine.

4. In a typographical machine, the combination of a channeled magazine, an escapement to control the release of type or matrices therefrom, and a spring-actuated arm adapted to be projected into the magazine by the releasing movement of the escapement, and acting when so projected to overcome the inertia of the released type or matrix and accelerate it in its passage from the magazine. 65

5. In a typographical machine, the combination of a channeled magazine, and an escapement to control the release of type or matrices therefrom and comprising a pair of pawls which are projected alternately into the magazine, the said escapement being also provided with a spring-actuated arm adapted to be projected into the magazine and acting when so projected to overcome the inertia of a released type or matrix and accelerate it in its passage 80 from the magazine. 85

6. An escapement comprising the rocking lever C provided with the matrix-releasing pawls D and E and also with the matrix-accelerating arm F . 90

7. An escapement comprising, in combination, the rocking lever C , the pawls D and E mounted thereon, the arm F also mounted on the lever C , and the spring F^2 connected to the arm F , for the purpose described. 95

8. An escapement comprising, in combination, the rocking lever C , the pawls D and E mounted thereon, and the spring-actuated arm F also mounted on the lever, 100 said arm being provided with the beveled nose F^3 , for the purpose described.

9. An escapement comprising, in combination, the rocking lever C , the pawls D and E mounted thereon, and the spring-actuated arm F also mounted on the lever, 105 said arm being formed with the recess F^1 , for the purpose described.

10. In a typographical machine, the combination of the channeled magazine A formed with the opening A^1 , the matrix accelerating arm F provided with the projecting nose F^3 standing normally in said opening, the said arm being movable into the magazine to free its nose therefrom, and the spring F^2 to give the arm its accelerating movement after it has been moved into the magazine. 110

11. In a typographical machine, the combination of the channeled magazine A formed with the opening A^1 , the matrix accelerating arm F provided with the projecting nose F^3 standing normally in said opening, the said arm being movable into the magazine to free its nose therefrom, and the spring F^2 to give the arm its accelerating movement after it has been moved into the magazine, the said nose F^3 being beveled so 115 120 125

as to engage the side of the opening A¹ when the arm is retracted and thereby return the arm to its normal position against the action of the spring.

5 12. In a typographical machine, the combination of a channeled magazine, the spring-actuated arm F movable into and out of the magazine, and formed with the notch

F¹, and the fixed pin G adapted to engage in the notch in one position of the arm F. ¹⁰

In testimony whereof, I have affixed my signature in presence of two witnesses.

DAVID SHERWOOD KENNEDY.
